[57] CLAIM

The ornamental design for a combined handle and position fixating device for use with a ground cloth, as shown and described.

DESCRIPTION

FIG. 1 is a front view of a combined handle and position fixating device for use with a ground cloth showing one embodiment of my new design;

FIG. 2 is a front view of a combined handle and position fixating device for use with a ground cloth showing a second embodiment of my new design;

FIG. 3 is a top view of the device shown in FIG. 1;
FIG. 4 is a top view of the device shown in FIG. 2.

FIG. 1

FIG. 2

FIG. 3

FIG. 4
